UNITED STATES PATENT OFFICE.

CHRISTIAN M. RUD, OF SLAYTON, MINNESOTA.

WIRE-STRETCHER.

1,259,559.

Specification of Letters Patent. Patented Mar. 19, 1918.

Application filed March 12, 1917. Serial No. 154,068.

To all whom it may concern:

Be it known that I, CHRISTIAN M. RUD, a citizen of the United States, residing at Slayton, in the county of Murray and State 5 of Minnesota, have invented certain new and useful Improvements in Wire-Stretchers; and I do hereby declare the following to be a full, clear, and exact description of the invention, such as will enable others skilled in 10 the art to which it appertains to make and use the same.

My invention relates to improvements in wire stretchers intended for general use, but especially adapted for use in the construction 15 or repairing of wire fences. To the above end, generally stated, the invention consists of the novel devices and combinations of devices hereinafter described and defined in the claim.

20 In the accompanying drawings, which illustrate the invention, like characters indicate like parts throughout the several views.

Referring to the drawings,

Figure 1 is a plan view of the improved 25 wire stretcher anchored to one of the posts of a barb wire fence and holding one of the wires thereof;

Fig. 2 is an edge elevation of the invention as viewed from the right, with respect 30 to Fig. 1;

Fig. 3 is a plan view corresponding to Fig. 1, with the exception that the lever is shown as temporarily used for placing the anchor chain under tension in securing the 35 wire stretcher to a post; and

Fig. 4 is a side view showing the wire stretcher as used when making a splice in a wire.

The numerals 5, 6 and 7 indicate, respectively, two of the posts and one of the wires of a barb wire fence. Staples 8 are used in securing the wire 7 to the posts 5 and 6.

The numeral 9 indicates the body of the improved wire stretcher and, as shown, its 45 outer longitudinal edge portion bears directly against the post 5 transversely of the wire 7 and on the opposite side thereof from the post 6.

Integrally formed on the sides of the body 50 9 and with each other, are the fixed jaws 10 of a pair of wire retaining grapples, oblique shoulders 11 and flanges 11'. The shoulders

11 project laterally outward from the body 9 and the flanges 11' extend along the outer edge portions of the body 9, between the 55 shoulders 11 and the tooth 12. These shoulders 11 and flanges 11' directly engage the post 5 and afford wide bearing surfaces which prevent the body 9 from tipping laterally on said post 5 under pulling strains. 60 The shoulders 11 also prevent endwise movement of the body member 9 toward the inside of the fence. Also laterally projecting from the body 9, in the same direction with the shoulders 11, the wide horizontal tooth 65 12 is adapted to engage the post 5 at a point inward from the shoulders 11 and thereby tends to hold said body against lateral twisting movement on said post and against endwise movement toward the outside of the 70 fence.

On one end of an anchor chain 15, is a snap 14, adapted to interlock with a pin held by the jaws of a bifurcated lug 13, on the body 9, in the vicinity of the operative faces 75 of the fixed jaws 10, and detachably connects said anchor chain to the body member 9. The intermediate portion of this anchor chain 15 is extended around the post 5 and its outer or free end portion is passed between a pair of laterally spaced curved fingers 16 formed on the inner end of the body 9 to afford a guide for said anchor chain. A wedge-like key 17, attached to the body 9 by a chain 18, is adapted to be inserted 85 through any one of the links of the chain 15 and reacts against the fingers of the guide 16 as a base of resistance for holding said chain under strain around the post 5.

Integrally formed with the inner end of 90 the body 9, is a lateral extension 19 which projects from the inner edge thereof and terminates in a curved hand piece 20. A hand lever 21 is fulcrumed to the lateral extension 19 for movement in the same horizontal plane with said body. On the short end of the hand lever 21, is a curved finger 22 adapted to be inserted through any one of the links of the chain 15 at the free end portion thereof, as shown in Fig. 3. Obviously, by moving the hand lever 21 into a position to carry its finger 22 toward the guide 16, inserting the same into one of the links of the anchor chain 15 and then mov-

ing said hand lever in a reverse direction, the anchor chain 15 may be placed under tension around the post 5. While the anchor chain 15 is thus held by the hand lever 21, 5 the key 17 may be inserted through one of the links of said chain to hold the same in a manner, as previously described. In case the anchor chain 15 cannot be placed under sufficient tension by a single operation of the 10 hand lever 21, the operation may be repeated, in which case the key 17 will have to be used for holding the anchor chain, while the hand lever 21 is moved into a position to secure another grip thereon. The strain 15 placed on the anchor chain 15 will cause the link thereof, together with the tooth 12, to sink into the post 5 and thereby assist in rigidly securing the wire stretcher to the post 5. It will be noted that the angle, between 20 the body 9 and its extension 19, is more than a right angle, so that, under a pulling strain on the anchor chain 15, the same will move between the fingers 16 and not drag over the adjacent end of the body 9. 25 The numeral 23 indicates the movable jaws of the wire-retaining grapples and they are intermediately pivoted by a nut-equipped bolt 24 to the inner end portion of the body 9 with their inner ends arranged for co- 30 operation with the fixed jaws 10. These movable jaws 23 are, as shown, made double ended, so that when one end thereof becomes worn, the same may be reversed end for end. A pair of pulling grapples is secured, one to 35 each side of the hand lever 21, and each of said pulling grapples comprises a fixed jaw 25 and a coöperating movable jaw 26. On each fixed jaw 25, is a lip 27, under which the free end of the respective movable jaw 26 works. A single nut-equipped bolt 28 pivotally connects both of the movable jaws 26 to the hand lever 21.

The ends of the coiled spring 29 are anchored, one to each of the movable jaws 26, 45 and its intermediate portion bears on the hand lever 21 as a base of resistance and tends to yieldingly hold the movable jaws 26 in coöperative arrangement with the fixed jaws 25. The movable jaws 26 are mounted 50 to move in the same direction with the movable jaws 23 and the wire 7 will be alternately held by the retaining and pulling grapples, as the same is placed under tension by the hand lever 21. A coiled spring 30, similar 55 to the spring 29, is provided for yieldingly holding the movable jaws 23 in operative positions. This spring 30 is not absolutely necessary, as the fixed jaws 23 will be automatically operated by the movement of the 60 wire 7 thereover and, in some cases, may be dispensed with.

By reference to Fig. 1, it will be noted that the wire 7 rests on the body 9 and hand lever 21, between the jaws of the retaining

and pulling grapples. By providing a complete set of grapples on each side of the wire stretcher, it is always possible to keep the wire 7 in this same position, no matter which side of the wire stretcher is turned up.

In stretching the wire 7 between the posts 5 and 6, the hand lever 21 is operated with a ratchet-like action. Under a movement of the hand lever 21 to stretch the wire 7, said wire will be securely held by the pulling grapple and free to slip, with respect to the retaining grapple. When the hand lever 21 is moved into a position to secure a new hold on the wire 7, said wire will be held against slippage by the retaining grapple and free to slip, with respect to the pulling grapple. 75 The lips 27 hold the free operative ends of the jaws 26 against lifting movement from the hand lever 21, under pulling strains by the wire 7, and they also hold said wires between the jaws of the pulling grapples. 80 As the wire 7 is moved between the jaws of the grapples, the movable jaws thereof, when engaged by the barbs of the wire, will open sufficiently to permit said barbs to pass there-between.

On the opposite end of the chain 15 from the snap 14, is a grapple 31, comprising a body member detachably secured to the chain 15 and having pivoted thereto a lever-equipped eccentric 32 arranged for coöperation with an abutment or lug 33 integral with said body member. In Fig. 4, the improved wire stretcher is shown as used when splicing the ends of two wires. In this use of the invention, the chain 15 is detached 95 from the body member 9 and its snap 14 secured in a hole in the hand piece 20. One end of one of the wires is held by the grapple 31 and the adjacent end of the other of said wires is held by the retaining and pulling grapples. With the wires thus held, the lever 21 may be manipulated to take the slack out of the wires and place the same under the desired tension. After the wires have been placed under the desired tension, 100 the overlapping ends thereof may be spliced in the customary or any desired manner.

From the above description, it is evident that the improved wire stretcher may be anchored to a corner post and a wire stretched 115 to said post and stapled, while held by the wire stretcher.

What I claim is:—

A wire stretcher comprising a post-engaging body member having an extension projecting outward at an angle thereto and also having a guide at the inner end of said extension, a lever fulcrumed to said extension for movement toward and from the body member and having an anchor chain-engaging finger, an anchor chain for securing the body member to a post and arranged to be extended through said guide and in position

to be temporarily engaged by said finger, whereby the anchor chain may be placed under strain, a key engageable with different links of the anchor chain and guide for holding the anchor chain, a wire-retaining grapple on the body member, and a wire-pulling grapple on the lever.

In testimony whereof I affix my signature in presence of two witnesses.

CHRISTIAN M. RUD.
